(57) **CLAIM**

I claim the ornamental design for the French fry carton holder and adaptor for use with vehicle cup holder, as shown and described.

DESCRIPTION

FIG. 1 is a front view of the French fry carton holder and adaptor for use with vehicle cup holder.

FIG. 2 is a rear view of the claimed design.

FIG. 3 is a side view of the claimed design.

FIG. 4 is a top view of the claimed design.

FIG. 5 is a bottom view of the claimed design.

FIG. 6 is a perspective view of the claimed design; and, FIG. 7 is a second perspective view of the claimed design in use with a French fry carton and seated in a vehicle cup holder.

The French fry carton and vehicle cup holder are depicted in broken lines as environmental matter forming no part of the claimed design.
